The ornamental design for a wiring panel for attachment to motor vehicle engines, as shown.

DESCRIPTION

FIG. 1 is a top plan view of a wiring panel for attachment to automobile engines showing my new design; FIG. 2 is a left side elevational view thereof; FIG. 3 is a rear elevational view thereof; FIG. 4 is a front elevational view thereof; FIG. 5 is a bottom plan view thereof; and, FIG. 6 is a top perspective view thereof.

FIG. 1**FIG. 2****FIG. 3**

FIG. 4

FIG. 5

FIG. 6

UNITED STATES PATENT AND TRADEMARK OFFICE
CERTIFICATE OF CORRECTION

PATENT NO. : Des. 330,007
DATED : October 6, 1992
INVENTOR(S) : Ron Francis

It is certified that error appears in the above-identified patent and that said Letters Patent is hereby corrected as shown below:

On the title page:

In the "Description", FIG. 1, line 2, delete the phrase "automobile engines" and in its stead place the phrase --motor vehicles--

Signed and Sealed this

Twenty-eighth Day of September, 1993
